ATTORNEYS.

UNITED STATES PATENT OFFICE.

REINHARD KOLLMAR, OF IRVINGTON, NEW JERSEY, ASSIGNOR TO FORSTNER CHAIN CORPORATION, OF IRVINGTON, NEW JERSEY, A CORPORATION OF NEW JERSEY.

CHAIN.

Application filed September 14, 1926. Serial No. 135,424.

This invention relates to an improved construction of ornamental chain, and has for its object to provide simple and effective means for applying decoration to a chain for personal wear.

A further object of the invention is to provide a construction of ornamental chain, the links of which may be readily connected one to the other without the use of solder, and at the same time provide ornamentation and secure the same in place.

A still further object of the invention is to provide a chain having elongated loop links and ring links with a decoration in the elongated loop links, and a means for securing the decoration in the elongated loop links and at the same time connecting the ring links to the loop links, all by bending of certain of the parts and without the use of solder.

With these and other objects in view, the invention consists of certain novel features of construction, as will be more fully described, and particularly pointed out in the appended claims.

25 In the accompanying drawings:

Figure 1 is a top plan view of the improved construction of chain.

Figure 2 is a side elevation thereof.

Figure 3 is a perspective view of the elongated loop link.

Figure 4 is a perspective view of the bar which is inserted into the elongated loop link.

Figure 5 is a perspective view of the member for securing the bar in the loop link and for connecting the loop link to the ring link.

Figure 6 is a perspective view of a loop link with ornamentation and the ring link partly secured thereto.

40 Figure 7 is a sectional side elevation of the construction shown in Figure 6.

Figure 8 is a perspective view of a modified form of loop link, with ornamentation and ring link secured thereto.

45 Figure 9 is a perspective view of a further modified construction of elongated link.

Figure 10 is a perspective view of a still further modified form of elongated link with decoration secured therein.

50 Figure 11 is a perspective view of the bar member used in the construction shown in Figures 9 and 10.

Figure 12 is a sectional elevation of a still different form of bar and U-connecting member.

In the construction of ornamental chains for personal wear such as watch chains, key chains or other chains for useful and decorative purposes, it is often found desirable to provide a chain having a series of elongated loop-like links and ring links, and to provide an attractive decoration for the elongated loop links and at the same time to secure the decoration in position and the loop link to its next adjacent ring link; and in order to accomplish this result, a bar is inserted into the loop link having notches in its edge and a U-shaped member is passed through the ring link and pressed into engagement with the bar to seat in said notches, thus securing the bar in the elongated link and connecting the ring link thereto. By providing the parts in this manner of separate pieces without soldering, a highly decorative link which is attractive in appearance may be constructed, 75 which comprises differently colored metals, such as yellow, green, white or red gold, thereby providing an unusually fancy link highly attractive in appearance; and the following is a detailed description of the present embodiment of this invention and showing one arrangement of parts by which the links of the ornamental chain may be decorated.

With reference to the drawings, 10 designates a ring-shaped link and 11 an elongated link, which may be of any suitable form having side arms 12 connected by end portions 13 and provided with an elongated opening 14 in which is mounted a bar 15 having notches 16 in its edges. The portions 17 which project beyond the side arms 12 of the elongated loop link and a U-shaped member 18 having side arms 19 with openings 20 therein is positioned to straddle the elongated loop link, 95 after first being passed through the ring link, and bent or compressed to seat in the notch 16, and to have its recess 20 interengage with or fit over the projecting portion 17 of the bar, thus securing the bar in its loop link and attaching the ring link to the loop link.

A pair of these U-shaped members 18 are provided, one engaging each end of the loop link, and a pair of U-shaped members pass through each ring link, as clearly illustrated in Figures 1 and 2, thus securing the different links of the chain together. The top surface of each loop link is recessed slightly as at 21 to permit the arms 19 of the U-link to seat therein to guide the same to proper po-

sition and prevent any relative lateral movement of the **U**-member and the loop link.

It will be readily understood that the loop link may be of various shapes, as illustrated at 22 and 23 in Figures 8 and 10; and it will also be apparent that the bar inserted between the side arms of the elongated link may be provided with spaced notches, as 24 in the bars 25 or 30, and an opening 26 in 10 the links 23 or 27 may be left, as will be apparent in Figures 9 and 10. It will also be understood that various other arrangements of recesses or projections between the bar and the loop member may be provided for interconnecting the two together as illustrated at 28 and 29 in Figure 12.

It will thus be seen that I have provided an ornamental chain constructed of four different parts, each of which may be of a gold 20 of a different color to render the same highly attractive and ornamental in appearance.

The foregoing description is directed solely towards the construction illustrated, but I desire it to be understood that I reserve 25 the privilege of resorting to all the mechanical changes to which the device is susceptible, the invention being defined and limited only by the terms of the appended claims.

I claim:

- 30 1. An ornamental chain comprising elongated loop links, a **U**-shaped slotted member having a reduced connecting portion, a bar extending thru the loop links and engaging the slots in the **U**-member, connecting 35 links engaging the reduced portion of the **U**-member to connect each adjacent link of the chain.
2. An ornamental chain comprising alternating elongated loop links and connecting 40 links, a **U**-shaped member having slots formed in the sides thereof, a bar extending thru the

loop links and protruding each side thereof and engaging the slots in the **U**-shaped member, connecting links passing thru the **U**-shaped members to connect each adjacent 45 elongated link.

3. An ornamental chain comprising elongated loop links and ring links, a **U**-shaped member having two slotted arms connected by a reduced bridge portion, a bar extending thru the loop link and protruding each side thereof and engaging the slots in the said **U**-member, a ring link engaging the reduced bridge portion of the **U**-shaped member to connect each adjacent elongated link. 55

4. An ornamental chain having elongated loop links, decoration for said links comprising a **U**-shaped member having a reduced central connecting portion, slots formed in the sides of said **U**-member, an elongated bar extending thru the loop link and protruding from each side thereof, said protruding portions extending into the slots in the sides of the **U**-member, and ring links passing thru the reduced portion of said **U**-member to connect each elongated loop link in the chain. 60

5. An ornamental chain having elongated loop links, decoration for said links comprising a **U**-shaped member having a reduced central connecting portion, slots formed in the sides of said **U**-member, an elongated notched bar positioned in the loop link and protruding each side thereof, the protruding portions of said bar extending into the slots in the **U**-member, the free ends of the **U**-member 70 being seated in the notches of said elongated bar, and a ring link engaging the reduced connecting portion of the **U**-member to connect each adjacent elongated link of the chain. 75

In testimony whereof I affix my signature.

REINHARD KOLLMAR.
